United States Patent Office

Des. 208,830
Patented Oct. 3, 1967

208,830

PACKAGING CONTAINER

William D. Stockdale, Arlington Heights, Ill., assignor to Illinois Tool Works Inc., Chicago, Ill., a corporation of Delaware

Filed Nov. 29, 1966, Ser. No. 4,853

Term of patent 14 years

(Cl. D58—12)

Fig. 1

Fig. 2

Fig. 4

FIG. 1 is a perspective view of a packaging container showing my new design;

FIG. 2 is a side elevational view thereof as viewed along line 2—2 of FIG. 4;

FIG. 3 is an end elevation thereof as viewed along line 3—3 of FIG. 4; and

FIG. 4 is a bottom plan view thereof as viewed along line 4—4 of FIG. 2.

I claim:

The ornamental design for a packaging container, as shown.
